(57) **CLAIM**

The ornamental design for a trunk and hip assembly for exoskeleton apparatus, as shown and described.

DESCRIPTION

FIG. 1 is a front view of a trunk and hip assembly for exoskeleton apparatus;

FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a perspective view thereof showing rear, top, and left sides;
FIG. 8 is a perspective view thereof showing rear, top, and right sides;
FIG. 9 is a perspective view thereof showing rear, bottom, and left sides;
FIG. 10 is a perspective view thereof showing rear, bottom, and right sides;
FIG. 11 is another perspective view of a trunk and hip assembly for exoskeleton apparatus showing rear, bottom, and right sides;
FIG. 12 is another perspective view of a trunk and hip assembly for exoskeleton apparatus showing rear, bottom, and left sides;
FIG. 13 is an enlarged fragmentary perspective view of that shown in FIG. 12 showing notches located on a portion of the trunk and hip assembly in greater detail, it being understood that the opposite side is a mirror image of that shown;
FIG. 14 is a perspective view of a trunk and hip assembly for exoskeleton apparatus showing top, front, and right sides;
FIG. 15 is an enlarged fragmentary perspective view of that shown in FIG. 14 showing a latch mechanism located on a spine portion of the trunk and hip assembly in greater detail;
FIG. 16 is a perspective view of a trunk and hip assembly for exoskeleton apparatus showing top, front, and left sides;
FIG. 17 is an enlarged fragmentary perspective view of that shown in FIG. 16 showing a light located on the right hip portion of the trunk and hip assembly in greater detail, it being understood that the opposite side is a mirror image of that shown;
FIG. 18 is a front view of the trunk and hip assembly for exoskeleton apparatus, shown with environment;
FIG. 19 is a rear view thereof; and,
FIG. 20 is a front right perspective view thereof.
The broken lines depict environment and portions of the article that form no part of the claimed design.
